UNITED STATES PATENT OFFICE.

WILLIAM OGLESBY PASSMORE, OF LIVERPOOL, ENGLAND, ASSIGNOR TO ASSOCIATED TELEPHONE AND TELEGRAPH COMPANY, OF KANSAS CITY, MISSOURI, A CORPORATION OF DELAWARE.

AUTOMATIC TELEPHONE SYSTEM.

Application filed October 12, 1927, Serial No. 225,614, and in Great Britain October 29, 1926.

The present invention relates to automatic or semi-automatic telephone systems and is more particularly concerned with systems in which arrangements are provided such that 5 certain privileged parties such as test clerks or toll operators can connect with busy lines and break down established or partly established connections thereon. Toll operators, for instance, will require to be able to break 10 down local connections in favor of long distance connections, since these are generally of more importance. The object of the invention is to enable this to be done readily and reliably in all the varied circumstances 15 which are likely to arise in practice.

According to the invention, this is attained in enabling a party, having obtained access to a busy line, to break down an established or partly established connection in response to the connection of a special potential 20 to the speaking leads.

According to another feature of the invention, use is made of a switch adapted to feed current to both calling and called parties in 25 which the feeding bridges comprise in each case a relay connected between one speaking lead and earth and an impedance coil connected between the other speaking lead and battery. With a switch of this type, when a toll operator wishes to break down an existing 30 connection, she applies earth to both speaking leads which is effective to shunt out either the line relay or the back bridge relay according as the wanted subscriber is the calling or called party. Moreover, it is 35 equally effective whether or not the calling party has replied and thus effected a reversal of current flow over the calling line.

In order that the invention may be more 40 fully understood and readily carried into effect, a telephone system according to the present invention will now be described by way of example with reference to the accompanying drawings. Figure 1 shows a rotary connector switch modified according to the 45 present invention to enable a toll operator to establish connection with a busy party and break down either an incoming or outgoing call.

Although the invention has been shown in Fig. 1 applied to a rotary connector it will 50 be understood that it is equally applicable to regular connector switches, or indeed any

switches adapted to feed battery to both calling and called parties.

A detailed description will be given of the arrangement shown in Figure 1. When the rotary connector RC is taken into use, impulse receiving relay A energizes in the following circuit: battery, resistance 54, resting contact and armature 32, resting contact and armature 45, normally closed contacts controlled by armature 11, negative line conductor, calling party's loop, positive line conductor, normally closed contacts controlled by armature 12, winding of relay A to earth. Relay A, upon energizing, completes the following circuit for release relay B: earth, armature 16 and its working contact, resting contact and armature 30, winding of relay B to battery. Relay B upon energizing earths the release trunk conductor RT from earth at the normally closed contacts controlled by armature 10, working contact and armature 18 to release trunk conductor RT; prepares a 75 switch holding circuit at armature 17; and at armature 19 completes the following circuit for relay J; earth, armature 19 and its working contact, resting contact and armature 29, winding of relay J to battery. Relay 80 J energizes and completes the following locking circuit for itself: battery, relay J, armature 13 and its resting contact, working contact and armature 19 to earth; and at armature 33 prepares the booster battery metering circuit. At armature 20, relay B opens a point in the 85 circuit of release magnet Z and prepares the impulsing circuit.

Relay A now responds to the next series of 90 impulses in the wanted number and effects the operation of the vertical magnet in accordance therewith. The first impulse of the first series is transmitted to the vertical magnet over the following circuit: earth, armature 16 and its resting contact, armature 20 and its working contact, normally closed off-normal springs N, vertical magnet V and series relay C to battery. Vertical magnet V and relay C energizes in series in this circuit 95 and upon the first vertical step of the switch, off-normal springs N and N¹ operate, so that subsequent impulses are repeated to the vertical magnet as follows: earth, armature 16 and its resting contact, armature 20 and its 100 working contact, spring N and its working 105 contact.

contact, armature 26 and its working contact, vertical magnet V and relay C to battery. Relay C which is operated by the first impulse of the series, remains operated owing 5 to its slow-to-release characteristics until all the impulses of the series are completed, after which it restores and switches the impulsive circuit from the vertical magnet V to the rotary magnet R.

10 The succeeding and final series of impulses is repeated to the rotary magnet R by relay A as follows: earth, armature 16 and its resting contact, armature 20 and its working contact, off normal spring N and its working contact, armature 26 and its resting contact, resting contact and armature 37, winding of slow relay E, armature 49 and its resting contact, rotary magnet R to battery. In response thereto, rotary magnet R steps the switch 15 shaft and wipers round to the desired contacts in the selected level. Relay E energizes with the first impulse and remains operated throughout the series due to its slow-to-release characteristic. Relay E, upon operating, disconnects the P¹ wiper at armature 39; at armature 40, connects the P² wiper over armature 48 and its resting contact to relay G; and at armature 41, provides an alternative circuit for the remaining impulses as relay G will energize in case the wipers pass over busy contacts. At the end of the series 20 of impulses, the wipers will be engaging the first line in the required P. B. X. group.

If this line is engaged, wiper P² will find 25 earth and the following circuit will be completed for relay G before relay E restores; earth, wiper P², armature 40, and its working contact, armature 48 and its resting contact, winding of relay G to battery. Relay G then operates and prepares the following 30 locking circuit: battery, relay G, resting contact and armature 48, normally closed contacts controlled by armature 40, working contact and armature 36, normally closed contacts controlled by armature 24, working contact and armature 17 to earth. Relay G upon 35 operating completes the following circuit for effecting the automatic rotary movement: earth, wiper P¹, (P¹ and P² contacts are strapped together on all but the last line of the group) resting contact and armature 39, armature 35 and its working contact, rotary interrupter springs 51, winding of relay K which is at this time shunted by resistance 40 54' and armature 25, winding of relay C to battery. Relay C operates in this circuit and at armature 25 removes the shunt from relay K and permits relay K to operate. Relay K upon operating completes the following circuit for the 45 rotary magnet R: earth, armature 17 and its working contact, armature 22 and its working contact, armature 49 and its resting contact, winding of rotary magnet R to battery. Rotary magnet R operates and advances the wipers on to the next set of contacts.

When the armature of the rotary magnet is fully attracted, the interrupter springs 51 open the circuit of relays K and C, and relay K restores and opens the circuit of the rotary magnet at armature 22. Relay C, however, does not release at this time due to its slow-to-release characteristic and during the time that relay C remains operated the earth on wiper P² maintains relay G energized. Relay G is slightly slow to release and should 70 the private wiper P² while rotating fail to bridge two adjacent busy contacts thereby disconnecting earth, relay G will remain operated until wiper P² finds earth at the next contact. If the next line is engaged, private 75 wiper P² will continue to find earth and relay K will operate again and operate rotary magnet R which will again step the wipers and so on until the last line of the group is reached unless a free line is encountered previously. 80 When the last line of the group is reached, wiper P¹ will not find earth on the private bank as the private bank contacts of this line are not strapped together, and therefore relays K and C will restore. Relay K, in releasing, 85 extends the busy circuit from conductor BS over armature 23 and armatures 42 and 38 to the positive line conductor. The calling party on hearing the busy signal will replace his receiver, causing relays A and B to deenergize and complete the following circuit for 90 release magnet Z: earth, armature 16 and its resting contact, armature 20 and its resting contact, off normal springs N¹ and release magnet Z to battery. 95

In case all the lines are not engaged, the private wiper P² instead of finding earth on the private bank contact of a free line will 100 find battery from the called subscriber's cut-off relay, and when relay G restores the following circuit is therefore completed for switching relay H; earth, armature 17 and its working contact, normally closed contacts controlled by armature 24, armature 36 and its resting contact, lower winding of relay 105 H, resting contact and armature 40, wiper P² to battery via the called subscriber's cut-off relay. Relay H, upon operating, at armature 47 locks up over its upper winding to earth at armature 17 of relay B. The cut-off 110 relay of the line-switch operates in series with the lower winding of relay H and is maintained operated by earth at armature 17 which extends over armature 46 and its working contact to wiper P². At armature 45, 115 battery through resistance 54 is disconnected from the line conductor —L, and battery through the lower winding of impedance I is connected thereto instead. The operation of relay H also opens the rotary magnet circuit at armature 49 to prevent further rotation, should the calling subscriber inadvertently operate his calling device; and at armatures 43 and 50 completes the ringing circuit. Interrupted ringing current is now 120 125 130

supplied from the generator lead GEN, upper winding of ringing trip relay F, resting contact and armature 27, working contact and armature 43 to the negative speaking conductor through the called party's bell and condenser to the positive speaking conductor, armature 50 and its working contact, armature 32 and its resting contact, resistance 54 to battery. An indication that the called subscriber's bell is being rung is given to the calling subscriber by an audible signal in his receiver since a small amount of ringing current flows over armature 44 and small condenser 52. On the called party's removing his receiver, relay F operates and closes a locking circuit for itself at armature 28 and cuts off the ringing current at the resting contacts of armatures 27 and 32 and at these same armatures completes the talking circuit. Current for speaking purposes is supplied to the called party from the upper winding of the impedance coil I and through the reversing relay D. As soon as this connection is established, relay D operates and reverses the direction of the current flow over the incoming speaking conductors, battery being connected to the incoming positive conductor from the lower winding of impedance coil I, armature 12 and its working contact, and earth to the incoming negative conductor through the winding of relay A and armature 11 and its working contact. When relay D operates, it also breaks the circuit of relay J at armature 13, but relay J being slow to release does not fall away immediately. While it holds up, booster battery from conductor BM is connected over resistance 53, armature 33 and its working contact, armature 10 and its working contact, working contact and armature 18 to the release trunk conductor RT and thereby operates the calling party's meter. After an instant relay J releases and disconnects booster battery from the release trunk, replacing the booster battery by earth potential at the normally closed contacts controlled by armature 33. The connector shown in Figure 1 is suitable also for dealing with individual lines in which case the bank contacts accessible to wipers P¹ and P² are not strapped together and therefore no automatic rotary operation will take place.

In order to explain the feature of the invention whereby an operator can release an established connection for the purpose of setting up a trunk call, it will be assumed that the connector has just established connection with a wanted party and that a trunk call then arrives for this party. The toll operator then extends a connection to the wanted line over a toll switching train by dialling his number in the usual manner and then connects earth to both speaking conductors, by the operator depressing a special key. The effect of earth in the positive conductor is to short-circuit relay D while that on the

negative line does not perform any useful function at this instance. Relay D releases and at armature 14 opens the circuit of release relay B. Relay B, upon deenergizing, removes earth at armature 18 from the release trunk, thereby allowing the preceding switches to release. 70

When the preceding switches have released, relay A deenergizes owing to the opening of its circuit and completes the following circuit for the release magnet Z; earth, armature 16 and its resting contact, armature 20 and its resting contact, off-normal springs N¹, winding of magnet Z, battery. It may be mentioned at this point that 75 the switch which establishes connection with an engaged line can be arranged to give the calling party a distinctive warning signal to indicate that the connection is wanted for a toll call and will be shortly disconnected. 80

Consider now the case in which the operator has a toll call awaiting a subscriber who is already engaged in an outgoing call set up over the connector shown in Fig. 1. Under these conditions the operator extends a 90 connection to the wanted line over a toll switching train by dialling the wanted number and then connects earth to both positive and negative speaking conductors as before. In this case the calling party's loop is holding relay A of the connector. 95

Assume first, that the called party has not yet answered and that accordingly relay D has not yet operated. The connection of earth potential to the incoming positive line 100 will in this case short-circuit relay A causing it to deenergize and open the circuit of relay B. With relays A and B in deenergized condition, the circuit of the release magnet is closed, and holding potential is 105 removed from the release trunk conductor so that the whole connection is cleared down.

Assume now that the wanted party has answered the call when the operator establishes connection with the calling party's line. Under these conditions relay D will be in operated position and the earth on the incoming negative conductor will now bring about the release of relay A with the results previously described. It will thus be seen that 115 by connecting earth potential to both conductors it is possible to bring about the release of the switch in either of the above two conditions.

What is claimed is:

1. In an automatic switch having a trunk terminating therein, a single wound line relay for controlling the operation and release of said switch normally connected to one conductor of said trunk line, and means for connecting said relay to the other conductor of said trunk line under certain conditions, said relay being maintained energized over its one winding only so that it will release when a certain potential is applied to both conductors. 125

ductors of said trunk line to cause the release of said switch regardless of which conductor said relay is connected to.

2. In a telephone system, an automatic switch, a trunk line terminating in said switch, a line relay normally connected to one conductor of said trunk line for controlling the operation of said switch to extend a connection to a called party, means for connecting said relay to another conductor of said trunk line operative when the called party answers, and means for causing said line relay to release said switch responsive to the application of a certain potential to both said conductors regardless of whether the called party has or has not answered.

3. In a telephone system, a connector switch for extending a call to a called line and for signalling the called subscriber, a ring-cut-off relay for interrupting the signalling when the call is answered, a back-bridge relay energized responsive to the operation of said ring-cut-off relay, and a release relay initially energized over a circuit including normally closed contacts on said ring-cut-off relay and subsequently energized over a circuit including contacts closed by the operation of said

back-bridge relay so that the release of said switch is under the control of said back bridge relay after the call is answered.

4. In a telephone system, a connector switch for extending a call from a calling to a called line, a line relay in the switch controlled over the calling line, a back-bridge relay in the switch controlled over the called line, a release relay for controlling the release of the connector energized over a circuit including contacts on said line relay, and means responsive to the answering of the call for including contacts on said back-bridge relay in said circuit.

5. In a connector switch for extending a connection, a line relay, a back-bridge relay, a release relay responsive to the operation of said line relay, and means effective after said back-bridge relay has been operated to cause the restoration of said release relay responsive to the release of said back-bridge relay.

In witness whereof, I hereunto subscribe my name this 15th day of September, A. D. 1927.

WILLIAM OGLESBY PASSMORE.
